UNITED STATES PATENT OFFICE.

CHARLES W. RODECKER, OF NEW YORK, N. Y.

WINDOW-SCREEN.

No. 857,759.

Specification of Letters Patent.

Patented June 25, 1907.

Application filed November 25, 1905. Serial No. 289,132.

To all whom it may concern:

Be it known that I, CHARLES W. RODECKER, a citizen of the United States, residing at New York, in the county of New York, 5 and State of New York, have invented a new and useful Window-Screen, of which the following is a specification.

This invention relates generally to window screens, and more particularly to that class in which the screen is combined with the upper and lower window sashes, whereby when the lower sash is raised and the upper sash lowered, the screens will be brought to operative position, and when the reverse movements of the sashes are effected, the screens will be hidden from view.

The objects of the present invention are to improve the manner of combining the screen carrying rollers with the window frame, to reinforce the screens against being blown inward by wind pressure, and at the same time to hold them tightly against the lower rail of the bottom sash and the top rail of the upper sash, thereby positively to preclude the entrance of insects from without.

With the above and other objects in view as will appear as the nature of the invention is better understood, the same consists in the novel construction and combination of parts 30 of a window screen, as will be hereinafter fully described and claimed.

In the accompanying drawings forming a part of this specification, and in which like characters of reference indicate corresponding parts, Figure 1 is a view in perspective, partly broken away, exhibiting the window frame and the sashes thereof equipped with the screens of the present invention. Fig. 2 is a vertical transverse sectional view. Fig. 40 3 is a horizontal sectional view taken on the line 3—3, Fig. 1. Fig. 4 is a perspective detail view of one of the screen carrying casings.

Referring to the drawings, 1 designates 45 generally the window frame, 2 the lower sash, and 3 the upper sash, and as these parts may be of the usual or any preferred construction, detailed description of them is deemed unnecessary.

As is shown, the sashes have combined 50 with them pairs of weights 4 and 5, the former of which is connected by cords or chains 6, in the usual manner with the lower sash, and the latter of which by cords 7 with the upper window sash. It is intended that the sashes shall slightly overbalance the weights,

so that when the sash locking mechanism, presently to be described, is released, the lower sash will raise and the upper sash will drop, and thereby effect the exposure of the screens. As is usual, the lower sash is heavier than the upper sash and for this reason the weights 4 are of greater weight than the weights 5, as clearly shown in Fig. 1.

It is one of the features of the present invention to combine the screen mechanism with the window casing without necessitating any extended change in its structural arrangement. This is accomplished by constructing the roller casings in such manner as they may readily be positioned relatively to the casing without the necessity of employing fastening devices for the purpose, and by the provision of suitable guides attached to the window casing in lieu of the ordinary guide sticks, which not only perform the function of causing the sashes to move properly within the casing, but also to check any tendency on the part of the screen to blow inward, or to sag away from the sashes and thus permit insects to enter.

The screen roller casings 8 and 9 are disposed at the upper and lower portions of the window casing as clearly shown in Figs. 1 and 2. Each casing, as shown in detail in Fig. 4, is a hollow rectangular structure made preferably of wood, and has secured adjacent to its terminals brackets 10 (one only being shown) that serve as bearings for the screen roller 11 which may be of the usual or any preferred construction and differs from the ordinary window shade roller in the fact that there is no stop mechanism employed to arrest the rotation of the roller.

Secured to the inner opposed faces of the stiles of the window casing are facing strips 12 to which are attached metallic guides 13, that are, as shown in Fig. 3, L-shaped in cross section, and have their upper and lower terminals bent at right angles to their length to form flanges 14 and 15, the guides being secured to the facing strips by screws 16. The flanges 14 are engaged by the underside of the casing 8 and are held combined therewith by screws 16, while the flanges 15 bear upon the upper side of the casing 9 and is secured thereto by screws 17. The flange member 18 of the guides project inward practically across the width of the side rails 19 of the lower sash, and are slightly spaced therefrom, for a reason that will presently appear.

Secured to the spacing beads 20 of the window casing are two guides 21 similar to the guides 13, that extend practically throughout the entire height of the casing 5 and their flanges 22 being spaced apart from the rear side of the upper sash for a reason that will presently appear.

The screen 23 of the lower roller carries at its upper end a batten or guard 24, which is 10 preferably of metal and is provided intermediate of its ends with an ear 25 through which passes a screw 26 to secure it to the lower rail of the sash. The ends of the batten project back of the flanges 18 of the 15 guides 13, as clearly shown in Fig. 2, and are thus positively held against yielding to wind pressure on the screen, and further the guides operate to hold the batten tightly against the lower rail of the sash and thus preclude entrance of insects, the flanges 18 also operating to accentuate this feature of the invention.

The screen 27 of the upper roller is secured to a batten or guard 28 similar to the batten 24, and is provided with an ear 29 which is 25 secured by a screw 30 to the upper rail of the lower sash, and on the inner face thereof. The terminals of the batten 28 are disposed between the inner face of the upper rail of the lower sash and the flanges 22 of the guides 30 21, as shown in FIG. 3, thereby to hold the batten combined with the rail, for the reason described in connection with the lower sash, the terminals of the screen 27 being also disposed back of the flanges 22 for the purpose 35 above described.

It will be seen that by the provision of the two sets of flanges 18 and 22 that the screens will be guided in the movement of the sashes and be held properly assembled for operation 40 therewith, so that there will be no danger of the screen blowing in and thus permitting entrance of insects and dust.

As a means for holding the two sashes against raising or lowering, except when desired, suitable locking mechanism is provided, one for the upper sash and one for the lower sash, as clearly shown in Fig. 1, and as these sash locking mechanisms are the same in both instances, a description of one will

serve for both. The sash lock, as shown in 50 FIG. 3, comprises two pivotally connected levers 31 and 32, one terminal of one of the members being provided with a push button 33 that projects through the facing strip, and the other member with a lug or toe 34 which 55 is adapted to engage a suitable socket 35 carried by one of the side rails of the sash. In order to hold the lug 34 normally in engagement with the socket, a leaf spring 36 is provided, one end of which is secured in any 60 suitable manner to the window casing, and the other end of which bears against the lever member 31.

When it is desired to bring a screen into operative position, the button 33 is pressed 65 inward, thereby throwing the lug out of engagement with the socket and freeing which ever sash the lug co-operates with.

Having thus described the invention, what is claimed is:—

1. The combination with a window casing of an upper and a lower sash mounted therein, screen casings secured within the window casing and constituting a window sill and window soffit, guide strips secured at their 75 opposite ends to the said screen casings and also being secured to the stiles of the window casing and forming guides for the sash and screen rolls mounted within the screen casings and being connected with the sash; 80

2. The combination with a window casing of an upper and lower sash mounted therein, screen casings secured within the window casing and constituting a window sill and window soffit, guide strips which are rectangular in horizontal section secured at their 85 opposite ends to the said screen casings and also being secured to the stiles of the window casing and forming guides for the sash and screen rolls mounted within the screen casings and being connected with the sash.

In testimony that I claim the foregoing as my own, I have hereto affixed my signature in the presence of two witnesses.

CHARLES W. RODECKER.
